UNITED STATES PATENT OFFICE.

ARTHUR G. LOGAN, OF MOUNT PLEASANT, PENNSYLVANIA.

VALVE.

1,371,795.

Specification of Letters Patent. Patented Mar. 15, 1921.

Application filed December 29, 1919. Serial No. 347,935.

To all whom it may concern:

Be it known that I, ARTHUR G. LOGAN, a citizen of the United States, residing at Mount Pleasant, in the county of Westmoreland and State of Pennsylvania, have invented certain new and useful Improvements 5 in Valves, of which the following is a specification.

This invention relates to valves for controlling the flow from fittings having inlets for more than one fluid and has for its object the provision of a simple, inexpensive and durable device by the use of which water of any desired temperature or a mixture 10 of any two liquids or gases may be drawn through a single outlet. The invention resides in certain novel features which are illustrated in the accompanying drawings and will be hereinafter first fully described 15 and then specifically pointed out in the appended claims.

In the drawings—

Figure 1 is an elevation of a valve embodying my present invention;

Fig. 2 is a vertical section through the same taken longitudinally of the inlets;

Fig. 3 is a horizontal section through the inlets showing different positions of the inlet-controlling valves;

Fig. 4 is a view partly in plan and partly in horizontal section;

Fig. 5 is a detail perspective view of the valve-controlling cam.

In carrying out my invention, I employ a valve casing 1 which consists essentially of a substantially cylindrical body having a closed bottom 2 and having an open top to receive a bonnet 3. In the wall of the body at diametrically opposite points thereof, I 35 provide inlet openings 4 and these openings are preferably defined by nipples 5 which are exteriorly threaded so as to be engaged in the ends of the pipes, one conveying hot water and one conveying cold water to the 40 valve casing. At a point intermediate the inlet openings, I provide an outlet opening 6 from which a spout 7 extends in the usual manner. Upon the inner wall of the valve casing or body, around the inlet openings, I 45 provide flat portions 8 which constitute seats for the valves 9 and 10. These valves, in the illustrated embodiment of the invention, consist of disks having their inner opposed surfaces convex, as shown at 11, and 50 having stems 12 extending from their outer flat faces. These stems may be of any de- sired formation and are illustrated as of tubular form having openings 13 in their inner portions whereby ample space is pro- 55 vided for the flow of water into the chamber 60 of the valve casing. The bonnet 3 is pro- vided with a central opening to receive the stem 14 of a cam 15, an adjusting nut or sleeve 17 being fitted around the stem and threaded through the opening in the bonnet 65 as shown. At the lower end of the nut or sleeve 17 is a seat 16 to engage the top of the cam 15 and prevent leakage, the adjust- 70 ment of the nut or sleeve compensating for wear and the engagement of the seat or rib 75 16 with the top of the cam forming in effect a ground joint. At the upper end of the stem 14 is secured a wheel or other form of handle 18 which is retained in position by a washer 19 and a nut 20, as will be readily 80 understood, and around the stem below the said handle I secure a collar 21 by a set screw 22, as shown. A pointer or marker arm 23 extends radially from the collar 21 and is properly shaped to clear the upper 85 projecting angular portion 24 of the bonnet 3 and ride over the laterally extended rim 25 at the upper end of the valve casing. Notches or grooves 26 are formed in the upper surface of the rim 25 and suitable 90 indicia are engraved or otherwise displayed upon the rim at each of said grooves, as shown most clearly in Fig. 4, to co-operate with the indicator 23 and enable the user to properly set the controlling cam or eccentric 95 so as to regulate the flow of water in the de- sired manner. The said operating cam or eccentric consists of a tapered body formed integral with or rigidly secured to the lower end of the stem 14 and having its lower ex- 100 tremity disposed between the valves 9 and 10. A guide pin 27 is fixed upon the bottom 2 of the valve casing and rises therefrom to engage a socket 28 in the lower end of the cam or eccentric so as to aid in bringing the 105 cam into its proper position when the parts are being assembled and also hold it in said position after the parts have been assembled. It will be readily noted upon reference to Figs. 2 and 4 of the drawings that the stem 110 14 and the guide pin 27 are so disposed relative to the faces 29 and 30 of the cam that the face 29 will be closer to a valve than the opposite face 30 when said faces are pre- 115 sented to the valves so that by bringing the cam into the proper position a desired mix- ture of hot and cold water may be drawn

and the temperature of the water thus controlled. It will also be noted that the cam is somewhat flattened or elongated so that the end surfaces 31 are farther apart than 5 the surfaces 29 and 30 and the pointer or marker arm 23 is so secured upon the stem 14 that it will lie in a radial plane of the stem which is approximately longitudinal 10 of the cam, that is to say, passes through the faces 31 of the cam and is disposed between the faces 29 and 30 thereof. It will thus be seen that if the marker points to the designation "Off" upon the rim 25 the cam will be so disposed that its ends 31 will bear upon 15 the respective valves and consequently the valves will be forced apart and against their respective seats so that no water will flow through the casing. The water exerts pressure 20 constantly upon the valves and, therefore, as the cam is turned to present the faces 29 and 30 toward the valves the pressure of the water will open the valves more or less according to the position of the cam. If the marker be brought to rest over 25 the designation "Hot" on the rim 25, the cam will be so disposed that its face 30 will be presented to the valve controlling the flow of hot water while one end surface 31 will have a portion in contact with the 30 valve controlling the flow of cold water so that the latter valve will remain closed while the former valve will open and by causing the cam to assume an intermediate position both valves will be opened and the hot and 35 cold water will mix within the valve casing and flow together through the outlet spout. A greater volume of hot or cold water may be drawn accordingly as the pointer is set at one or the other of diametrically opposite 40 positions so that when mixed hot and cold water are being drawn the temperature may be regulated as desired.

My improved valve is exceedingly simple in the construction and arrangement of its 45 parts and is, therefore, not apt to get out of order. It may be readily assembled or dis-

assembled and may be, therefore, produced and installed at a very low cost. While the device is intended more particularly for domestic use in drawing water, it may be employed to control the flow of any two liquids or gases which are, at times, to be mixed. 50

Having thus described the invention, what is claimed as new is:

1. A device for the purpose set forth comprising a casing having diametrically opposed inlet ports and an outlet port intermediate the inlet ports, valves controlling the flow through the inlet ports and tending normally to open under pressure of inflow- 55 ing fluid, a cam mounted for rotary movement between the valves and comprising a downwardly tapered body having opposed faces at unequal distances from its center of rotation and other faces connecting the first- 60 mentioned faces and disposed at equal distances from the center of rotation and at a greater distance therefrom than either of the first-mentioned faces, a stem rising from said cam, means at the bottom of the casing 65 for rotatably supporting said cam, and means secured upon said stem for rotating the cam.

2. A device for the purpose set forth comprising a casing having opposed inlet ports 70 and an outlet port intermediate the inlet ports, valves controlling the flow through the inlet ports and opening inwardly under pressure of inflowing fluid, a fixed pin rising from the bottom of the casing between 75 the inlet ports, a cam having its lower end fitting rotatably over and resting on said pin, the cam bearing constantly on the inner faces of both valves, a stem rising from the cam through the top of the casing, and a 80 sleeve fitting in the top of the casing around the stem and having its lower end bearing directly on the upper end of the cam, said 85 sleeve being adjustable along the stem.

In testimony whereof I affix my signature. 90

ARTHUR G. LOGAN. [L. s.]
